UNITED STATES PATENT OFFICE.

EDWIN LESLIE BISHOP, OF BIRMINGHAM, ENGLAND.

APPARATUS FOR USE IN COVERING CARDBOARD AND LIKE BOXES.

Application filed October 3, 1924. Serial No. 741,483.

To all whom it may concern:

Be it known that I, EDWIN LESLIE BISHOP, a subject of the King of Great Britain, residing at 44^a Deritend, Birmingham, in the county of Warwick, England, have invented Improved Apparatus for Use in Covering Cardboard and like Boxes, of which the following is a specification.

The present invention has relation to apparatus for use in covering cardboard or like boxes with paper; more particularly, for turning over the protruding edges of paper applied to the wall of the box, into the interior and securing it, to enhance the appearance of the box edge, the present improvements having for their object to provide for this operation being carried out more expeditiously and efficiently than heretofore.

According to the present invention, the box is adapted to be supported along at least two of its walls in an open-sided carrier with which it can be readily engaged and disengaged by a lateral movement (i. e. a movement in a plane with its base), as for instance by manipulation and the paper edging is adapted to be turned down and secured on to the interior faces of at least two of the walls of the box by means of a frame or part having projecting fingers, brushes, or the equivalent, adapted to be reciprocated into and out of the box.

The fastening operation of the edging may be assisted by a reciprocatory movement of the carrier.

The present invention further comprehends apparatus for covering cardboard and like boxes, wherein there is provided in combination, an L or angle shaped carrier adapted to support the box along two of its sides, an L or angle shaped member carrying projecting fingers, brushes, or like devices, and means for rectilinearly displacing the aforesaid member for the turning-down operation of the protruding paper edge of the box.

Still further, the present invention comprehends apparatus for covering cardboard and like boxes, wherein there is provided in combination an L or angle shaped carrier adapted to support the box along two of its sides, an L or angle shaped member car-

rying projecting fingers or like devices, means for slidably displacing or reciprocating the aforesaid member, to bring the fingers or like devices to cooperate laterally with the carrier, for the turning-down operation of the protruding paper and means for reciprocating or rectilinearly displacing the carrier laterally of the fingers or like devices for the sealing or pressing of the turn-over paper.

An angle or L-shaped member may be fixedly incorporated, over which the fingers or like devices are adapted to slide for guiding and finger cleaning purposes, for which latter purpose the member may be longitudinally grooved.

The edge of the box carrier may be rubber lined or covered where it is adapted to cooperate with the fingers in the turning or pressing operation.

The fingers in their withdrawn position may lie adjacent the edge of the box carrier and are so shaped as to initially bend the protruding paper at right angles to the wall of the box, or substantially so, when the box is placed on the carrier. Forward movement of the fingers or the like towards the box turns the paper on to the inside of the box. The fingers remain stationary whilst the box is reciprocated by its carrier being firstly elevated to firmly seal the turn-over paper, and then depressed to permit of the withdrawal of the fingers.

Two sides of the box are operated upon simultaneously and on account of the open-sided nature of the L-shaped carrier, the box is readily inserted and withdrawn.

A one-revolution clutch may be employed, such as is well known in box making and like machinery for enabling the operative parts of the device to always rest in an initial or commencing position.

In order that this invention may be clearly understood and readily carried into practice, reference may be had to the appended explanatory sheet of drawings, upon which:

Figure 1 is a perspective view of a machine for turning over the protruding paper edges of cardboard boxes, constructed according to the present invention.

Figure 2 is an enlarged elevational frag-

mentary view of the machine shown in Figure 1, viewed from the left hand side thereof.

Figure 3 is a section taken on the line 3^a 3^a of Figure 2.

Figure 4 is a section taken on the line 4^a 4^a of Figure 2, and

Figure 5 is a section taken on the line 5^a 5^a of Figure 2.

10 Figure 6 illustrates in perspective one of the fingers hereinafter referred to.

In an embodiment of the present invention, the carrier 1 is itself of angle formation having a connecting web 2 across the 15 limbs, thereby comprising a corner element wherein the box can be quickly placed and removed with its base against the web 2 and two of its walls adjacent the limbs of the carrier. The web 2 may be laterally adjustable to accommodate the carrier to boxes 20 of different depth, this being conveniently provided for by slotted arms 3 on the web engaging screw clamping means 4 on the carrier 1. A rubber edging 5 is counter-sunk along the edges of the limbs of the carrier 1 remote from the web. This carrier 25 at or about its corner point carries an obliquely set frame 6 adapted to slide in the oblique guides 7 which are conveniently set 30 at an angle of 45° and carried by the structure 8. An L shaped frame 9 is fixedly mounted on the structure 8 adjacent the rubber edging 5 of the carrier and is centrally grooved along its length as at 10.

35 A slidable L-shaped frame 11 corresponding somewhat to the fixed L-shaped frame 9 is mounted alongside that member, and comprises two clamping elements adapted to hold a series of metal fingers 12. Any 40 number of these metal fingers 12 may be employed, according to the length and breadth of the box and are adapted to be carried by the vertical as well as the horizontal limb of the part 11. Their extremities 45 13 may be shaped according to the tasks they have to perform, for example, that finger at the corner may be shaped differently to the adjacent ones operating on the flat. The sliding frame 11 may be carried 50 by a base 14 which has a sliding relationship with the top or table part 15 of the structure 8. The fingers may be readily interchangeable and their outer or operative extremities 55 normally terminate substantially flush with the edge of the carrier 1. It will be noted on reference to Figure 2 that one side or limb of the box carrier 1 and also of the finger carrier frame 11 is vertical and the other side horizontal, and that the guide frame 6 and guides 7 are inclined at an angle of 45° so that the box carrier which is caused to move with the frame 6 laterally with respect to itself and in a plane which is at an equal angle to each of said sides of the box 60 carrier and finger carrier and hence the

65 fingers are arranged for relative movement to the same extent toward and from the two sides of the box carrier between movements of the latter and its frame 6. Both carrier 1 and slidable frame 11 are adapted to be 70 actuated from a suitable power shaft 16 (Figure 3). The power shaft may have an eccentric on it which rocks a lever 18 on a pivot 19, and is connected by a rod 20 to the slide 14 carrying the slidable frame 11. The cam slot 21 is so shaped that when the fingers 12 are drawn home towards the box carrier 1, there is a period of rest during 75 which such carrier is reciprocated for the pressing or completing operation of the turnover. Further, a suitable cam 22 on the power shaft 16 may operate one limb of a bell-crank lever 23, the other limb of which is attached to a second bell-crank lever 24 (see particularly Figure 5), adapted to actuate the slide 6 of the carrier 1. 80

85 The power shaft 15 may be driven from a pulley 25 by way of a one revolution clutch 26 (Figure 1) operable by foot mechanism 27 or suitable hand mechanism. Such a one revolution clutch is well known in box making and like machinery and ensures the carrier 1 and member 11 always assuming the position illustrated when the clutch is 90 thrown open.

95 The timing of the parts is such that the slidable frame 11 is firstly moved towards the carrier 1, the fingers passing over the rubber edging 5 thereof. The carrier is then reciprocated upwardly and then downwardly 100 and the fingers are then withdrawn.

In operation, the box having had the bending paper strip or covering piece attached thereto, with its edging projecting beyond the edge, and already covered with 105 adhesive, is placed in the carrier member with its base against the web and end wall against the upright limb of the carrier and side wall against the base or horizontal limb. During the operation of placing or 110 positioning the box the projecting paper edge is brought into contact with the extremities 13 of the fingers and is bent substantially at right angles to the wall of the box. The apparatus is then set in operation; 115 the slidable frame 11 causing the fingers to move the already bent paper edging inwardly, folding it on to the inner face of the box, the reciprocatory movement of the carrier 1 securely sealing it, and the fingers are then withdrawn. In this manner two 120 edges of the box are finished and the other two are then operated on in a similar manner. The fingers are automatically cleaned as they pass over the groove 10. On account 125 of the open nature of the carrier 1, boxes can be very speedily placed in position and removed by the operator.

130 What I claim as my invention and desire to secure by Letters Patent is:—

1. In apparatus for covering boxes, a box carrier, a relatively fixed wiper element, a finger carrier, fingers carried by said finger carrier, means to move said finger carrier toward and from the box carrier longitudinally with respect thereto so that the fingers pass over the wiper element and partly over the box carrier, and means to impart relative reciprocating lateral movement to the said carriers to cause the fingers to move to and from the sides of the box carrier. 5 of said finger carrier, said finger carrier being arranged for longitudinal movement 50 toward and from the front end of the box carrier to pass the fingers partly thereover and withdraw the same therefrom.
2. In apparatus for covering boxes, a box carrier open on one side and having angularly related sides, a relatively fixed wiper element, a finger carrier having angularly related sides corresponding with those of the box carrier, fingers carried by said sides of the finger carrier, means to move said finger carrier toward and from the box carrier longitudinally thereof so that the fingers pass over the wiper element and partly over the box carrier, and means to impart relative reciprocating lateral movement to the said carriers to cause said fingers to move toward and from said sides of the box carrier. 15 5. In apparatus for covering boxes, a box carrier and a finger carrier each having two angularly related sides, said box carrier being arranged for lateral movement toward and from the finger carrier in a plane which is at an equal angle to each of said sides of said finger carrier, said finger carrier 55 being arranged for longitudinal movement toward and from the front end of the box carrier to pass the fingers partly thereover and withdraw the same therefrom, and a wiper arranged for contact with said finger 60 during such movement of the latter.
3. In apparatus for covering boxes, a box carrier open on one side and having angularly related sides, a relatively fixed wiper element, a finger carrier having angularly related sides corresponding with those of the box carrier, fingers carried by said sides of the finger carrier, means to move said finger carrier toward and from the box carrier longitudinally thereof so that the fingers pass over the wiper element and partly over the box carrier, and means to impart lateral reciprocating movement 20 to the box carrier to cause said sides thereof to move toward and from the fingers of the finger carrier. 6. In apparatus for covering boxes, a supporting frame, a box carrier open on one side and having angularly related sides, means mounting said box carrier on said frame for lateral movement of said carrier in a plane at an equal angle to each of said sides of said carrier, means to impart such movement to such carrier, a wiper element 25 mounted on said frame and arranged at the front side of said box carrier, a finger carrier having angularly related sides corresponding to those of said box carrier, fingers on said finger carrier, means mounting said finger carrier on said frame for reciprocating movement of said finger carrier toward and from said wiper and the front side of said box carrier to pass said fingers over and from said wiper and said sides of the box carrier, and means to impart 30 such movement to said finger carrier. 75
4. In apparatus for covering boxes, a box carrier and a finger carrier each having two angularly related sides, said box carrier being arranged for lateral movement toward and from the finger carrier in a plane which is at an equal angle to each of said sides 35 of said finger carrier, said finger carrier being arranged for longitudinal movement 40 toward and from the front end of the box carrier to pass the fingers partly thereover and withdraw the same therefrom.
5. In apparatus for covering boxes, a box carrier open on one side and having angularly related sides, a relatively fixed wiper element, a finger carrier having angularly related sides corresponding with those of the box carrier, fingers carried by said sides of the finger carrier, means to move said finger carrier toward and from the box carrier longitudinally thereof so that the fingers pass over the wiper element and partly over the box carrier, and means to impart lateral reciprocating movement 45 to the box carrier to cause said sides thereof to move toward and from the fingers of the finger carrier. 80
6. In apparatus for covering boxes, a supporting frame, a box carrier open on one side and having angularly related sides, means mounting said box carrier on said frame for lateral movement of said carrier in a plane at an equal angle to each of said sides of said carrier, means to impart such movement to such carrier, a wiper element mounted on said frame and arranged at the front side of said box carrier, a finger carrier having angularly related sides corresponding to those of said box carrier, fingers on said finger carrier, means mounting said finger carrier on said frame for reciprocating movement of said finger carrier toward and from said wiper and the front side of said box carrier to pass said fingers over and from said wiper and said sides of the box carrier, and means to impart 50 such movement to said finger carrier. 85
7. In apparatus for covering boxes, a box carrier element and a paper edge turning element, said elements being arranged for relative lateral movement and also for relative movement longitudinally over said box carrier element and means to impart such movements successively to such elements. 90

In witness whereof I have hereunto set my hand.

EDWIN LESLIE BISHOP.
